US00D583743S

(12) **United States Design Patent**
Swinson, III

(10) **Patent No.:** US D583,743 S
(45) **Date of Patent:** ** Dec. 30, 2008

(54) **WHEEL CHOCK**

(75) Inventor: **William E. Swinson, III**, Greeneville, TN (US)

(73) Assignee: **Meco Corporation**, Greeneville, TN (US)

(**) Term: **14 Years**

(21) Appl. No.: **29/304,100**

(22) Filed: **Feb. 25, 2008**

DESCRIPTION

FIG. 1 is a perspective view of the wheel chock;

FIG. 2 is a right side view of the design embodiment shown in FIG. 1;

FIG. 3 is a top side view of the design embodiment shown in FIG. 1;

FIG. 4 is a bottom side view of the design embodiment shown in FIG. 1; and,

FIG. 5 is a front side view of the design embodiment shown in FIG. 1.

The broken lines are for environmental purposes only and form no part of the claimed design.
